UNITED STATES PATENT OFFICE.

HUGH LEE, OF CAESAR, MISSISSIPPI.

TRACK CONSTRUCTION.

1,257,945.

Specification of Letters Patent. Patented Feb. 26, 1918.

Application filed December 14, 1917. Serial No. 207,049.

To all whom it may concern:

Be it known that I, HUGH LEE, a citizen of the United States of America, residing at Caesar, in the county of Hancock and State 5 of Mississippi, have invented certain new and useful Improvements in Track Constructions, of which the following is a specification.

This invention relates to railroad track 10 constructions and more particularly to an improved type of rail and means for joining the same in connection with tracks which have to be frequently moved. For example, in logging operations the tracks frequently 15 have to be shifted with the necessity of loosening and removing the fastening employed for joining the rails end to end. Some of the fastenings heretofore employed have been reasonably secure but have been 20 difficult to remove and replace. Others have been easy of removal but have been open to the objection that they did not securely hold the rails, with the result that under the hard usage to which the tracks were subjected the 25 rails would become separated.

A fastening for use under the conditions above mentioned must unite the rails securely because, owing to the temporary nature of the tracks, they must conform to the 30 grade of the ground, no attempt being made to provide a carefully graded road-bed. As the present description proceeds it will be seen that the present invention provides a type of track and fastening means therefor 35 particularly adapted for use in the relation indicated, though it is to be understood that it is capable of use in many other relations. For example, when heavy machinery is to be moved, such as a steam shovel for instance, it is customary to lay a track ahead 40 of the shovel upon which it may travel. Only a few sections of track are needed, the track in the rear being taken up and placed in front of the shovel as the shovel proceeds. The present invention will be found 45 of use in such relations as these.

Further objects and advantages of the invention will be set forth in the detailed description which now follows:

50 In the accompanying drawing—

Figure 1 is a perspective view illustrating two rails joined by means of the invention;

Fig. 2 illustrates the rails separated;

Fig. 3 is a horizontal section illustrating

a slightly modified form employing two key-plates instead of one;

Fig. 4 is a view of one of the bridge plates; and

Fig. 5 is a perspective view of a filling 60 piece hereinafter described.

Referring to the drawing 5 and 6 designate the rails of a track of the character above indicated. These rails are of channel formation and comprise vertical inner webs 65 10, horizontal tread flanges 8 and horizontal base flanges 9. The webs 10 are cut away at their abutting ends 7 and present shoulders 11. This results in forming a recess or pocket 12 at the ends of the rails when 70 the rails are brought together end to end for a bridge-plate 13 which is of such length as to overlap the two recessed portions of the rails and fit snugly between the shoulders 11. The plate 13 carries studs 14 adapted 75 to engage in openings 15 formed in the webs 10. While I have illustrated only one stud and only one opening for each rail, it is apparent that these may be duplicated if desired. The flanges 8 and 9 of the rails 80 are longitudinally grooved at 16 and 17 respectively to provide channels in which key-plates 18 may slide. The channels 16 and 17 are of such length that the key-plates 18 85 may be slid away from the confronting ends 85 of the rails to a point beyond the shoulders 11, at which time it will be possible to place bridge-plate 13 in position or to remove such bridge-plate, but when a key-plate is moved to overlie the bridge plate it is apparent 90 that the bridge plate is held against lateral movement and the ends of the rails are securely locked together. It is immaterial whether one key-plate is employed at each rail joint or whether two of said plates are 95 employed, one for each rail, it being only necessary, in order to secure the desired results, to provide an element which will overlap plate 13 and prevent its lateral movement. To prevent the key-plates 18 from 100 working end-wise after they have been moved to position to overlap the bridge plates 13, I may if desired, employ filling 105 pieces 19 of such shape and length as to fill the channel 17 and lie within said channel between the inner end of the channel and the inner end of the key-plate.

From the foregoing description it will be seen that simple and efficient means are provided for accomplishing the objects of the 110

invention, but while the elements shown and described are well adapted to serve the purposes for which they are intended, it is to be understood that the invention is not limited to the precise construction set forth but includes within its purview such changes as fairly come within the spirit of the appended claims.

Having described my invention, what I claim is:

1. The combination with a pair of rails of channel formation, of a bridge plate of such length as to overlap the abutting ends of the rails, lugs carried by said bridge plate, said rails being provided with openings for the reception of said lugs and means mounted for longitudinal sliding movement upon said rails and outwardly of the bridge plate and movable to and from a position in front of said bridge plate.
2. A structure as recited in claim 1 embodying means for preventing said longitudinally sliding member from moving endwise with respect to the rails.
3. A device of the character described, comprising a pair of rails of channel formation having open sides and having their vertical portions adjacent their ends recessed to provide pockets, a bridge plate adapted to have a seating in the pockets of adjacent rails when said rails are brought together, interengaging means between the bridge

plates and the rails for preventing longitudinal separation of the rails, longitudinal key-ways formed in the upper and lower portions of the rails and key-plates movable in said key-ways.

4. In a track construction, a pair of rails of channel formation comprising vertical webs and horizontal outwardly projecting tread and base flanges, longitudinal key-ways formed in the confronting faces of said flanges, a key-plate movable in said key-ways, a bridge plate of such length as to overlap said rails, said rails being recessed for the reception of said bridge plate and interengaging members between the rails and the bridge plate for preventing endwise separation of the rails, said key plate being movable to and from a position in front of the bridge plate.

5. The combination with a pair of rails of channel formation of a bridge plate of such length as to overlap the abutting ends of the rails, interengaging means between the bridge plate and the rails for preventing longitudinal separation of the rails and means mounted for longitudinal sliding movement upon said rails and outwardly of the bridge plate and movable to and from a position in front of said bridge plate.

In testimony whereof I affix my signature.

HUGH LEE.
